(57) **CLAIM**

The ornamental design for a skateboard, as shown and described.

DESCRIPTION

FIG. 1 is a front perspective view of a skateboard, which embodies my design.

FIG. 2 is a front view of the skateboard of FIG. 1.

FIG. 3 is a rear view of the skateboard of FIG. 1.

FIG. 4 is a right side view of the skateboard of FIG. 1. The left side view is a mirror image of the right side view.

FIG. 5 is a top view of the skateboard of FIG. 1; and,

FIG. 6 is a bottom view of the skateboard of FIG. 1.

The broken lines in FIG. 6 represent portions of the skateboard that form no part of the claim.

1 Claim, 5 Drawing Sheets# US D770,585 S
